[57] CLAIM

The ornamental design for an Ozark log splitter, as shown and described.

DESCRIPTION

FIGS. 1 through 4 are shown fragmented to indicate that, for ease of illustration, a precise length of the article is not claimed.

FIG. 1 is a front elevational view of the Ozark log splitter showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.
